UNITED STATES PATENT OFFICE.

JAMES A. STORMS AND THEODORE A. ARNOLD, OF NORTH TARRYTOWN, N. Y.

CAR-COUPING.

SPECIFICATION forming part of Letters Patent No. 336,871, dated February 23, 1886.

Application filed July 2, 1885. Serial No. 170,532. (No model.)

To all whom it may concern:

Be it known that we, JAMES A. STORMS and THEODORE A. ARNOLD, citizens of the United States, residing at the village of North 5 Tarrytown, in the county of Westchester and State of New York, have invented certain new and useful Improvements in Car-Couplings, of which the following is a specification, reference being had therein to the accompanying 10 drawings.

Figure 1 is a front view of a car-coupling with our invention applied thereto. Fig. 2 is a horizontal section on the line 2 2, Fig. 1. Fig. 3 is a vertical section on the line 3 3, Fig. 15 1. Fig. 4 is a vertical section of the draw-head on the line 4 4, the sliding jaws and their operating devices being removed. Fig. 5 is a perspective view of the coupling-bar detached. Fig. 6 is a section on the line 6 6, Fig. 5, looking 20 upward.

A represents the draw-head, which may be attached to a car in any preferred manner. It is provided with a flaring mouth or throat, which guides the coupling-bar to the engaging 25 jaws, as is usual in car-couplings, our invention differing from those usually employed in dispensing with the top and bottom walls of the throat, for a purpose which will be described.

30 B B' represent the sliding coupling-jaws, which normally project out into the throat of the draw-head in the path of the coupling-bar, the front edges of these jaws being beveled, so that as the end of the coupling-bar 35 comes in contact therewith they shall be forced into the chambers K formed for their reception in the sides of the draw-head.

30 C C are springs, which operate to force the sliding blocks or jaws B B' outward into the 40 throat of the draw-head. They may be of any form or character, though we have shown for the sake of illustration and prefer to use those of a spiral form, situated between the jaws B B' and the rear walls of the chambers K, the 45 springs surrounding pins c, which hold them in proper position to operate with the greatest advantage against the sliding jaws.

b b are apertures in the sliding blocks, which 50 permit them to slide over the pins c as they (the blocks) are forced into their respective seats or chambers K.

In order to effect the uncoupling of the cars, we connect the sliding jaws with a lever situated upon one side of the draw-head, which simultaneously moves the jaws in opposite directions into their seats or sockets and releases the coupling-bar.

E F are bars or links sliding in grooves or ways L M, formed in the draw-head, and connected, respectively, at their inner ends with 60 the jaws B B', and at their outer ends to the operating-lever G in the manner to be described.

In order that the lever G may work in the most satisfactory manner, the outer projecting 65 end of one of the sliding bars should lie above the other, and for the sake of convenience and simplicity in construction we arrange the bar F above bar E throughout its entire length, though the ways or slots L M might be in the 70 same horizontal plane, and only the outer end of one of the links lie above the other. The groove L is deeper and longer than the one M, in order that the link or bar E may pass in rear of the curved seat a for the head of the 75 coupling-bar in rear of the jaws B B', and engage with the jaw B by means of a pin or abutment, D, carried thereby, and projecting rearwardly into the path of the link E.

D' is a pin projecting from the rear face of 80 the jaw B' into the way or slot M, and extending through an aperture or slot formed in the lever F near its inner end. It will now be seen that if the link E be thrust inward, and the link F be drawn outward, the sliding jaws 85 B B' will be withdrawn into their seats K against the pressure of the springs, thus leaving the throat of the draw-head perfectly free for the removing of the coupling-bar.

We have shown a method of attaching the 90 operating-lever G to the bars E F which allows of this movement—that is, the simultaneous withdrawal of the jaws. The lower bar, E, is extended somewhat beyond the end of bar F, and is provided with a recess or seat, H, the 95 bar F being provided with a rectangular hole or aperture, I, the bar being expanded at this point to give the requisite strength, should this be found necessary. The lever G passes through aperture I and into the recess or seat H, where it is pivoted at h. It will be seen that if the lever is moved in the direction of

the arrow, Fig. 1, the links or bars E and F will be shifted in opposite directions, the one E inward and the one F outward, and that the sliding jaws will be thereby drawn or forced into their seats within the chambers K. The lever G may be extended to the top of the car, or it may be fitted with any mechanism which will permit it to be operated from either or both sides of the car, as may be found most desirable; and it will also be understood that our invention would be operative were the links E and F and the lever G arranged horizontally instead of vertically.

While we have shown a loose or detachable connection between the sliding jaws and their operating links or bars, yet this is not essential, as these connections may be permanent and rigid, although we prefer the forms shown. The bar E is shown as cut away upon its front edge at e, in order to permit it to slide to the necessary extent past the seat a without interference from the coupling-bar.

The various chambers K L M within the draw-head may be formed during the process of casting by cores, the draw-head being thus formed of a single piece of metal, in which case the pins c may be put in place by drilling holes for their reception and inserting them from the outside; or the draw-head may be made of two or more cast pieces bolted or otherwise secured together. However the draw-head may be formed, it will be seen that all the operative mechanism is concealed within and protected by the draw-head, the only exposed parts being the ends of bars E and F and the operating-lever, this arrangement being advantageous, as it protects the springs and other parts of the mechanism, which would be liable to become broken were they unprotected.

N represents the coupling-bar, having arrow-shaped ends, the shoulders n of which engage with the jaws B B'. The thickness or vertical dimension of the bar is much greater than in coupling-bars as now ordinarily employed, and is greater than the thickness of the jaws with which it engages, and also preferably greater than the thickness of the draw-head, this construction enabling us to couple together cars the draw-heads of which vary considerably in height, and yet permit the bar to lie in a substantially horizontal plane, in which position the bar operates most advantageously.

n' n' are shoulders at the top of the bar N, and projecting a short distance toward the center of the bar from the shoulders n. When the coupling is in place, these shoulders n' rest upon the top of the jaws B B', and prevent it from falling below and out of reach of the jaws, as it would otherwise do, owing to the absence of the lower wall of the mouth or throat of the coupler. Should one of the jaws fail to engage with the corresponding shoulder, n, of the coupling-bar as it is forced into the throat of the draw-head, the bar will still be

held, and the movement imparted to it from the car will force it into place behind the two jaws, even though at first it fail to be properly caught.

The coupling-bar may be permanently fastened to the car by chain, if desired, and may be also provided with apertures n², to reduce its weight and the amount of metal required for its manufacture.

We have shown the draw-head provided with a recess, O, and pin-hole o, adapted to receive an ordinary coupling link and pin, which may be employed should it be necessary to couple a car provided with our device with one having the old style of coupler.

We are aware that car-coupling devices consisting of gripping-jaws, springs which force the jaws toward each other, and mechanism for opening the jaws have been used in combination with substantially arrow-headed coupling-bars, the engaging heads of which are longer than the vertical dimensions of the gripping-jaws, and we do not claim such devices, broadly, as our invention; but we believe ourselves to be the first to have constructed a rigid draw-head, the throat of which is without top or bottom walls, and to mount in such a rigid draw-head gripping-jaws projecting out into the throat of the draw-head, such an arrangement permitting the use of our jaw-operating mechanism, and at the same time being particularly adapted for use in combination with a coupling-bar of the character herein described.

What we claim is—

1. The combination of the draw-head provided with the chambers K, sliding jaws mounted in said chambers, coiled springs situated between the jaws and the rear walls of the chambers, the pins c, projecting from the rear walls of the chambers and serving as supports for the springs by which they are surrounded, and a lever connected with said jaws, adapted to simultaneously move them in opposite directions against the springs, the said jaws being provided with sockets b, whereby they may slide over pins c as they are drawn within the chambers, substantially as set forth.

2. The combination of a draw-head, the sliding jaws, springs which force said jaws into the throat of the draw-head, links or sliding bars connected one with each sliding jaw, and both extending to the same side of the draw-head, and a lever which simultaneously moves said links to force the jaws out of the throat of the draw-head, substantially as set forth.

3. The combination of a draw-head, the sliding jaws, springs which force said jaws into the throat of the draw-head, links or sliding bars connected one with each sliding jaw and both extending to the same side of the draw-head, said links being of different lengths, and a lever situated at the side of the draw-head, and connected with said links and adapted to simultaneously move them and the

jaws in opposite directions, substantially as set forth.

4. The combination of a draw-head, the sliding jaws, springs which force said jaws into the throat of the draw-head, links or sliding bars connected one with each jaw and both extending to the same side of the draw-head, the outer end of one of the links being situated directly over the outer end of the other link, and a lever connecting the ends of said links and adapted to simultaneously move them and the jaws in opposite directions, substantially as set forth.

5. The combination of the draw-head, the sliding jaws, the springs which bear against said jaws, links connected with the sliding jaws and extending to one side of the draw-head, one link lying above the other, and a lever connected to said links and adapted to move them and the jaws in opposite directions, substantially as set forth.

6. The combination of the draw-head provided with a throat for the entrance of a coupling-bar, sliding jaws situated upon opposite sides of said throat, springs which bear against said jaws, links connected with said jaws and extending to one side of the draw-head, one of said links passing in rear of the throat in the draw-head, and a lever connected to said links and adapted to move them and the jaws in opposite directions, substantially as set forth.

7. The combination of the draw-head, the sliding jaws B B', said jaws being provided, respectively, with rearwardly-projecting pins D D', link E, which bears against the pin D, link F, which engages with pin D', said links extending to one side of the draw-head, and a lever connected with said links and adapted to move them and the jaws in opposite directions, substantially as set forth.

8. The combination of the draw-head, the sliding jaws, the spring bearing against the jaws, links connected at their inner ends to the jaws and extending to one side of the draw-head, and a lever pivoted to one link and projecting through an aperture in the other link, whereby it is adapted to move said links simultaneously in opposite directions, substantially as set forth.

9. A draw-head having a throat for the entrance of the coupling-bar, chambers K K, situated upon opposite sides of the throat for the reception of the gripping-jaws, and the ways L M, connected, respectively, with the opposite chambers K and extending both to the side of the draw-head, and adapted to receive the jaw-operating levers, substantially as set forth.

10. The combination of a rigid draw-head provided with a throat for the entrance of the coupling-bar, having side guiding-walls, but without top or bottom walls, sliding gripping-jaws mounted within said rigid draw-head, mechanism which operates said jaws, and a coupling-bar which engages with said jaws, and is provided with stops or shoulders which prevent the bar from falling out of engagement with the gripping-jaws, substantially as set forth.

11. The combination, with a rigid draw-head provided with a throat for the entrance of the coupling-bar, having side guiding-walls, but without top or bottom walls, sliding gripping-jaws mounted within said rigid draw-head, and mechanism which operates said jaws, of a coupling-bar adapted to engage with said jaws, provided with stops which prevent the bar from falling out of engagement with the jaws and being of a vertical dimension greater than the thickness of the draw-head, substantially as set forth.

12. A coupling-bar provided at its opposite ends with substantially arrow-shaped heads adapted to engage with gripping-jaws, the bar being of a vertical dimension greater than the gripping-jaws with which it engages, and provided, also, at its upper edge, in proximity to the arrow-shaped heads, with outwardly-projecting shoulders n' n', substantially as and for the purposes set forth.

In testimony whereof we affix our signatures in presence of two witnesses.
